UNITED STATES PATENT OFFICE

JOHN GREEN KERSHAW AND ROBERT DAWSON, OF MONTREAL, QUEBEC, CANADA

BUNCH BUILDING ON BOBBINS

Application filed April 13, 1929. Serial No. 354,917.

The invention relates to bunch building on bobbins, as described in the present specification and illustrated in the accompanying drawings that form part of the same.

5 The invention consists essentially of the novel features of construction pointed out broadly and specifically in the claims for novelty following a description containing an explanation in detail of an acceptable 10 form of the invention.

The objects of the invention are to build up a small bunch of yarn at the base of the bobbin for the purpose of maintaining the continuity of the operations until the feeler 15 operates the mechanism for discharging the empty bobbin to be replaced by a full bobbin from the battery or magazine and to do this by means of a cam mechanism forming an addition to the cam mechanism for operating 20 the ring rail of a ring spinning machine; to effect this precaution against misspicks without affecting the efficiency of such machines or adding complications, that will materially increase the cost of production 25 and maintenance; and generally to provide a mechanism for the purposes aforesaid of a simple and durable character and readily adaptable to modern machinery.

In the drawings, Figure 1 is an elevational 30 view of a section of a ring frame machine showing the tilting ring frame, operating lever and the centre of the bevel driving gear broken away to disclose the mechanism of this invention.

35 Figure 2 is an end elevational view of the driving gear and cam mounting and clutch member.

Figure 3 is an enlarged elevational detail 40 of the cam mechanism showing a fragmentary view of the lever in engagement with the bunch builder cam.

Figure 4 is an enlarged detail of the cam showing it in clutch for bobbin winding purposes.

Figure 5 is a cross sectional view of the cam mechanism on the line 5-5 in Figure 4.

Figure 6 is a detail showing the shaft mounting and clutch member.

50 Figure 7 is a sectional detail of the cam

for operating the bunch builder cam plate on the line 7-7 in Figure 6.

Figure 8 is a detail of the bunch builder cam plate.

Figure 9 is an enlarged detail of a shuttle 55 containing the bobbin.

Figure 10 is a detail of a bobbin showing the feeler slot.

Figure 11 is a detail of the feeler.

Figure 12 is a vertical sectional view corresponding to Figure 2 and showing the cam shaft in longitudinal section and the external cam in vertical section.

Like numerals of reference indicate corresponding parts in the various figures. 60

Referring to the drawings, the heart shaped cam, indicated by the numeral 15 may be herein termed the external cam, which controls the traverse of the ring frame operating lever 16 which is pivoted at 17 and oscillates in conformance with the rotation of said cam to accomplish its purpose, which contributes to the winding of the bobbin 18, and while certain parts are illustrated in connection with the winding of this bobbin, they 70 all form part of the mechanism which is already in extensive use and may be called conventional or familiar in the trade. Therefore in this invention by an initial revolution of the cam shaft without rotating the 75 cam 15 a reserve bunch of yarn is built up at the base of the bobbin prior to the actual winding thereof.

The external cam 15 is rigid with the hub 80 19 and is to receive the shaft head 29 and at 21 to receive the dog 35, the slot 23 extending inwardly through the rim of the cam and forming a receptacle for the loose cam plate 24, said cam plate 24 having the slots 25 and 26 through which the pins 27 and 28 extend in order to loosely hold the cam plate 24 to the cam 15, that is to say, when the cam 15 is rotating and causing the traverse of the ring frame lever, the cam plate 24 maintains 95 its inner position.

The circular flange 29 having a notch 30 and forming a clutch member extends outwardly from the outer end of the hollow cam shaft 31 having the internal cam 32 in the 100

an internal cam behind said clutch member, a cam or push plate having pin slots and pins therein rigidly secured to said external cam and passing through said slot to said lever at each operation of the internal cam, and a dog having a tooth spring-held to its engagement with the aforesaid clutch member in idle and fast positions of said clutch.

5 3. In bunch building on bobbins and operating mechanism, a pivoted lever, a cam shaft suitably journaled and driven, an internal cam and clutch member in fixed relations to said shaft, an intermediate cam plate forming the operating connection from said 10 cam to said lever, an external cam carrying said cam plate and loosely mounted on said cam shaft, and a clutch member pivotally mounted on said external cam and spring-held to the aforesaid clutch member.

15 4. In bunch building on bobbins and operating mechanism, a pivoted lever, a cam shaft suitably journaled and driven, an internal cam and a clutch member in fixed relations to said shaft, an external cam loosely 20 mounted on said cam shaft and recessed and slotted, a push plate slidably mounted in the slotted external cam and forming a reach member from said internal cam to impart motion to said lever, a clutch member pivotally 25 mounted on said external cam and engaging the aforesaid clutch member following the operating engagement of said push plate with said lever and bringing the external cam into operating engagement with 30 said lever.

35 Signed at Montreal, Canada, this 16th day of February, 1929.

JOHN GREEN KERSHAW.
ROBERT DAWSON.
